(57) CLAIM

The ornamental design for a single serving beverage container, as shown and described.

DESCRIPTION

FIG. 1 is a front elevational view of a single serving beverage container including a closing lid showing my new design;

FIG. 2 is a right side elevational view thereof, the left side elevational view being a mirror image thereof;

FIG. 3 is a rear elevational view thereof;

FIG. 4 is a perspective view thereof;

FIG. 5 is a bottom plan view thereof;

FIG. 6 is a top plan view thereof;

FIG. 7 is a front elevational view of the single serving beverage container with the lid removed for ease of illustration;

FIG. 8 is a top plan view thereof; and,

FIG. 9 is a bottom plan view of the single serving beverage container with the cup portion removed for ease of illustration.
